UNITED STATES PATENT OFFICE.

ALBERT E. MCGILL, OF CHICAGO, ILLINOIS.

FOLDING PERAMBULATOR OR GO-CART.

No. 861,475.

Specification of Letters Patent.

Patented July 30, 1907.

Application filed May 12, 1906. Serial No. 316,476.

To all whom it may concern:

Be it known that I, ALBERT E. MCGILL, a citizen of the United States, residing at Chicago, in the county of Cook and State of Illinois, have invented certain new and useful Improvements in Folding Perambulators or Go-Carts, of which the following is a full, clear, and exact specification.

My invention relates to folding perambulators or go-carts for small children adapted to be folded into a compact form, and it has for one of its important objects to provide simple and efficient means whereby the back of the seat may be extended or inclined as desired to suit the comfort and ease of the child.

Another object of the invention is to provide improved and simple means whereby the folding of one pair of wheels will also cause the other pair to make a like movement.

A still further object of the invention is to provide certain details in the construction of the device which will especially adapt it for being made with a wooden frame, thereby reducing the cost of manufacture over constructions heretofore employed.

With a view to the accomplishment of these ends and certain other objects which will hereinafter appear, the invention consists in the features of novelty which will now be described with reference to the accompanying drawings and then more particularly pointed out in the claims.

In the said drawings—Figure 1 is a side elevation of a go-cart constructed according to this invention with the handle broken away. Fig. 2 is a plan view thereof. Fig. 3 is a side elevation or edge view of the device folded up. Fig. 4 is an end view thereof. Fig. 5 is an enlarged detail perspective view of one of the rear corners of the running gear frame and connected parts. Fig. 6 is an enlarged detail section taken on the line 6, 6 Fig. 1. Fig. 7 is an enlarged detail section taken longitudinally of one of the side bars of the seat frame. Fig. 8 is a perspective view of one end of the locking bolts or rods hereinafter described. Fig. 9 is a perspective view of one of the bars of the running gear frame, showing the groove in which said rod slides. Fig. 10 is a fragment of Fig. 7 showing a different adjustment of the extension. Fig. 11 is a detail cross section on the line 11, 11 Fig. 7, and Fig. 12 is an enlarged transverse section taken on the line 12, 12 Fig. 1, the wheel being omitted.

The running gear frame is composed of two side bars 1, 2 which are connected together at their forward ends 50 by a transverse rod 3. These side bars may be composed of any suitable material but if composed of wood as is advantageous in point of cheapness, they will constitute separate parts from the rod 3, which may be in the form of an elongated bolt passing through the ends 55 of the bars 1, 2 and also serving as a pivotal support for the lower or forward end of the side bars 4, 5 of the

seat frame. In this example of the invention these side bars 4, 5 are composed of tubing or made hollow as better shown in Figs. 7 and 10, so as to receive the branches 6 of an extension which is composed of said 60 branches and a cross bar at their upper ends, and these parts are of a construction similar to that shown in my application filed Dec. 5, 1904, Serial No. 235,529. This extension 6, 7 is also composed of tubing and is adapted 65 to slide freely in the bars 4, 5 so as to be withdrawn any desired extent and thereby impart a corresponding extension and inclination to a flexible back portion 8 of the seat 9. This flexible back portion 8 passes over a rod 10 supported under the cross bar 7 by means of thumb nuts 11 screwed on the ends of stems 12 which 70 pass through the cross bar 7 so that when desired the supporting bar 10 may be caused to clamp the flexible back extension 8 firmly against the under side of the bar 7 and thereby hold the back extension 8 at the desired adjustment, preventing it from sagging more 75 than required: In order that the back extension 8 may not slip entirely out of its position between the bars 7, 10, it is provided at its extremity with a welt 13 of greater diameter than the ordinary distance between 80 the said two bars.

In the use of the back extension the cross bar 7 is pulled upwardly or rearwardly after the thumb nuts 11 have been loosened until the desired degree of inclination and extension is attained, and it may then be locked in position by a pin 14 inserted in any one 85 of a series of perforations or sockets 15 in one of the branches 6, at a point above the upper end of one of the side bars 4, 5, thus preventing the branches of the extension from slipping back into the side bars 4, 5. The back extension 6, 7 is prevented from being 90 pulled entirely out of the side bars 4, 5 by a catch 16 adapted to engage in a perforation or socket 17 at the upper end of one of the side bars 4, 5. This catch is in the form of an U shaped spring situated within the branch 6 and having a lug 17a embedded in the 95 wall of said branch on one end and a V shaped hook 18 arranged in an aperture 19 in the opposite side wall of said branch and bearing normally against the inner face of side bar 5 so that when it arrives at the socket 17 it will drop into it but on account of its V shape 100 or beveled form it will disengage from said socket when the branch 6 is pressed downwardly.

The cross bar 7 of the back extension connects the upper ends of the side bars 4, 5 together and constitutes therewith an U shaped seat frame which is 105 adapted to be folded down into close relation to the two side bars 1, 2 of the running gear frame, and as shown in Fig. 2 it is narrower than the running gear frame and is adapted to be embraced by folding handle when the latter is turned downwardly into place 110 on top of the running gear frame so that the three members occupy in depth the thickness of only two

of them. This folding handle is composed of two side bars 20 connected at their lower ends to the rear ends of side bars 1, 2 by means of ordinary hinges 21, while their upper ends are connected together by handle bar 22. As is shown in Fig. 3 the handle frame is longer than the seat frame so as to project over and entirely embrace the latter when folded up.

The seat 9 is suspended from the hinged seat frame by seat fabrics 23 and these are attached to the side bars 4, 5 by means of rods 24 similar in construction to that shown in my U. S. Letters Patent No. 771,386, October 4, 1904. The upper ends of these rods are bent around the side bars 4, 5 as shown at 25 and thus connected thereto while their lower ends are attached 15 to the side bars 4, 5, by nuts 26 passing through the upper sides of the side bars 4, 5, but resting against the under sides, see Fig. 7, and being screwed upon threaded extensions 27 of the rods 24, or any other suitable means of adjustment may be employed. The 20 seat fabric 23 may be prevented from sliding down the rods 24 in a manner similar to that shown in the above referred to application, that is by means of pins or screws 28 and offsets or bends 29 in the rods 24, these parts being so related that the fabric 23 is pressed into 25 the bend or offsets 29 by the screw or pin 28, thereby preventing the fabric from sliding. These bends or screws 28 are the means whereby a clip or collar 30 is held on each of the side bars 4, 5 for attaching the upper ends of seat supporting braces 31 thereto. The 30 lower ends of these braces 31 are connected to the side bars 20 respectively of the handle by means of links 32 so that when the handle is folded forwardly it will force the lower ends of the braces 31 in the same direction and thereby automatically cause them to fold 35 up with the folding seat frame 4, 5. When the seat frame is in position for use the lower ends of the braces 31 are supported and held in place by a cross rod 33 secured thereto in any suitable way and projecting over the side bars 1, 2 of the running gear frame, as 40 better shown in Figs. 5 and 12. As the cross bar 33 is moved back into operative position by the straightening out of the handle into the position shown in Fig. 1, it automatically locks into engagement with two catches 34, one at each side of the running gear frame. 45 The rear ends of these catches 34 are supported on a cross rod 35, which may also constitute the pintle of the hinges 21, if desired, and which is connected to the catches 34 in such a way that when a toe piece 36 on the rod 35 is pressed the catches 34 will release the 50 bar 33, permitting the handle to be folded forwardly. The catches 34 may also be connected together for the sake of greater security by a cross rod 37. When the cross bar 33 is in operative position as shown in Fig. 5, it is held against the possibility of rising upwardly 55 by guards 38, one on each of the side bars 1, 2.

39, 40 are the front and back wheel forks or brackets, a pair of which is journaled to each of the side bars, 1, 2, of the running gear frame by means of collars 41, 42 respectively, and the front fork 39 is rigidly 60 connected to the rear fork 40 by means of a rod 43 secured thereto in any suitable way so that when the wheel fork at one end of the running gear frame is folded under the frame as shown in Figs. 3 and 4, the fork at the other end will make a similar movement 65 without special attention. In order that these forks

may be rigidly locked against rotary movement when in operative position, the upper side of each of the side bars 1, 2 is provided with a longitudinal groove 44, an example of which is shown in Fig. 9, and in each of these grooves is situated a longitudinally movable bolt or locking rod 45, which, if desired, may be round, and which passes through offsets 46 in collars 41, 42 and consequently holds these collars against rotary movement. These rods 45, however, are formed with notches 47 so that when moved longitudinally 75 the requisite distance the notches will come opposite the offsets 46 and permit the collars 41, 42 to rotate around the bars 1, 2 and locking bolts or rods 45. When the locking rods 45 are in their locked position they may be so held by catches 48 secured to the collars 41 and engaging rings 49 formed on rods 45 and embracing bars 1, 2. For the better support of the cross bar 33 its ends are turned downwardly as shown at 33^a over the said offsets of the collars 42, thus holding the bar 33 against longitudinal movement and 80 avoiding the possibility of the ends thereof slipping out from between the offsets 46 and guards 38. The collars 41, 42 are split or divided as indicated at 42^b on the collar 42 as an example, so that they may be inserted over the side bars 1, 2 and embedded therein 85 to prevent them from moving longitudinally thereon, the divisions of the collar being afterwards secured together by a nut and bolt 42^b or other suitable means. 90

Having thus described my invention what I claim as new therein and desire to secure by Letters Patent, is

1. In a perambulator the combination of a seat frame, a seat, a flexible, extensible back portion to said seat, an extension on said seat frame, means for adjustably connecting said back portion and extension together, and means 100 for supporting and carrying said seat frame.
2. In a perambulator the combination of a seat, a flexible, extensible back portion therefor, a seat frame supporting said seat, an adjustable extension on said seat frame, and means whereby said flexible back portion may be connected to said extension at any desired point in the length of said back portion, with means for supporting and carrying said seat frame. 105
3. In a perambulator the combination of a seat, a flexible, extensible back portion therefor, a seat frame, an adjustable extension thereon, and a clamp for connecting said extension and extensible back portion together, with means for supporting and carrying said seat frame. 110
4. In a perambulator the combination of a seat, a flexible, extensible back portion therefor, a seat frame, an adjustable extension on said frame, a rod between which and said extension said back portion passes, and means whereby said rod is caused to clamp said back portion, with means for supporting and carrying said seat frame. 115
5. In a perambulator the combination of a seat frame, a seat frame extension telescoped therewith, a seat supported on said frame, a flexible back portion and means whereby said back portion may be secured to said extension at the desired point in the length thereof, with means for supporting and carrying said seat frame. 120
6. In a perambulator the combination of a seat frame comprising tubular side bars, a seat frame extension comprising a cross bar and branches inserted in said side bars, a seat supported on said side bars, a flexible back portion, a clamping bar adjustably secured longitudinally of said cross bar and between which clamping bar and cross bar said back portion is supported, and means for supporting and carrying said seat frame. 125
7. In a perambulator the combination of a seat frame comprising tubular side bars, a seat frame extension comprising a cross bar and branches inserted in said side bars, means for locking said branches and side bars together in various positions of adjustment, a seat supported on said 135

side bars, a flexible back-portion for said seat, and means whereby said back portion is adjustably secured to said cross bar, with means for supporting and carrying said seat frame.

5 8. In a perambulator the combination of a seat frame, a seat frame extension comprising a cross bar, a clamping rod arranged longitudinally of said cross bar and having threaded ends passing therethrough, thumb nuts screwed on said threaded ends for clamping said bars together, a seat supported on said seat frame, a flexible back portion for said seat passing between said cross bar and clamping bar and means for supporting and carrying said seat frame.

9. In a perambulator the combination of a seat frame, a seat, side fabrics for supporting said seat, rods secured to said seat frame and around which said side fabrics are looped at their upper edges, said rods having offsets or bends, means pressing said fabric into said offsets or bends for preventing the same from sliding down said rods and means for supporting and carrying said seat frame.

10 10. In a perambulator the combination of a running gear frame, a seat frame pivotally supported at its forward end thereon, seat frame braces pivoted at their upper ends to the upper end of said seat frame, a handle hinged to said running gear frame, links connecting said handle to the lower ends of said seat frame braces, a cross bar connecting the lower ends of said braces together, a latch for engaging and locking said cross bar when the braces are in their operative position.

11. In a perambulator the combination of a running gear frame, a seat frame hinged at its forward end thereto, seat frame braces pivoted at their upper ends to the upper end of said seat frame, a handle hinged to said running gear frame, links connecting said handle to the lower ends of said braces, a cross bar connecting the lower ends of said braces together, guards on said running gear frame under which said cross bar engages when the said braces are in operative position, and latches for engaging and locking said cross bar.

12. In a perambulator the combination of a running gear frame, a seat frame hinged at its forward end thereto, seat frame braces pivoted at their upper ends to the seat frame, a cross bar connecting the lower ends of said braces together, two latches engaging the ends of said cross bar respectively, and means connecting said latches together whereby they will move in unison.

13. In a perambulator the combination of a running gear frame comprising side bars, wheel brackets rotatably connected to said side bars and connected together in pairs so as to move in unison, a sliding, locking bar partially embedded in each of said side bars and each being common to two of said brackets, and means whereby the movement of said bars in one direction will lock said brackets against rotary movement.

14. In a perambulator the combination of a running gear frame, comprising side bars, wheel brackets rigidly connected together in pairs, collars on each of said brackets rotatably mounted on said side bars and having offsets, a locking rod partially embedded in each of said side bars and passing through said offsets for locking said collars against rotary movement, said rods having notches adapted to be moved into register with said collars for permitting the collars to rotate.

15. In a perambulator the combination of a running gear frame comprising side bars, wheel brackets, collars journaling said brackets upon said bars and having offsets, and locking rods slidable longitudinally of said side bars into engagement with said offsets for holding the collars against rotary movement.

16. In a perambulator the combination of a running gear frame comprising side bars, wheel brackets, collars journaling said wheel brackets upon said side bars and having offsets, locking rods having rings embracing said side bars and extending longitudinally thereof into engagement with said offsets for locking said collars against rotary movement.

17. In a perambulator the combination of a running gear frame comprising side bars, divided collars surrounding and embedded in said side bars, wheel brackets carried by said collars respectively, and means for locking

said collars against rotary movement on said side bars at will.

18. In a perambulator, the combination of a seat frame, a seat supported by the frame, a seat frame extension longitudinally adjustable with respect to the seat frame, means for holding the extension in an adjusted position, a flexible back portion, means for securing the back portion to said extension at the desired point in the length thereof, and means for supporting and carrying said seat frame. 85

19. In a folding perambulator the combination of a folding seat supporting structure, a forwardly and rearwardly moving locking bar connected with said structure, a hinged handle connected with said structure for causing it to fold downwardly when the handle is moved forwardly and downwardly and to rise to position for use when the handle is raised, and a pivoted catch stationary with relation to said locking bar and adapted to engage the same and hold the seat supporting structure and handle in position when the handle is raised. 95

20. In a folding perambulator the combination of a horizontal running gear frame, a folding seat supporting structure supported thereon and adapted to fold lengthwise thereof and in close relation thereto, a locking bar connected with the seat supporting structure and movable thereby along the running gear frame as said structure is folded and unfolded, a handle hinged to the rear end of the running gear frame and pivotally connected with the said structure for raising said structure into position for use or lowering it to its folded position as the handle is raised or lowered, and a catch pivotally fixed to the running gear frame for engaging and holding said locking bar when the handle is raised to position for use. 100

21. In a folding perambulator the combination of a horizontal running gear frame, a folding seat supporting structure supported thereon and adapted to fold into a position lengthwise thereof, a locking bar connected with the seat supporting structure and having sliding support on the running gear frame, said locking bar being movable along the running gear frame by the seat supporting structure as the said structure is folded and unfolded, a handle hinged to the lower end of the running gear frame and pivotally connected to said structure for raising the structure to position for use when the handle is raised and folding the structure towards the running gear frame as the handle is lowered, and a catch pivotally fixed to the running gear frame for engaging and holding said locking bar when the handle is raised to position for use. 115

22. In a folding perambulator the combination of a folding seat supporting structure, a forwardly and rearwardly moving locking bar connected with said structure, a hinged handle connected with said structure for causing it to fold downwardly when the handle is moved forwardly and to rise to position for use when the handle is raised, a forwardly projecting catch fixed against movement with said locking bar pivoted on a horizontal axis and adapted to engage and hold said bar against movement when the handle is raised, and a downwardly movable toe piece connected with said catch whereby the catch may be released by the pressure of the foot of the operator. 120

23. In a folding perambulator the combination of a horizontal running gear frame, a folding seat supporting structure supported thereon and adapted to fold into a position lengthwise thereof, a locking bar connected with the seat supporting structure and having sliding support upon the running gear frame and being movable back and forth on the running gear frame as the seat supporting structure is folded and unfolded, a handle hinged to the running gear frame and pivotally connected with the seat supporting structure for raising and lowering the seat supporting structure as the handle is raised and lowered, and a forwardly projecting catch having a beveled end arranged in the line of movement of said locking bar for engaging and holding the bar when the handle is raised to position for use and thereby holding both the handle and the seat supporting structure against folding movement. 140

24. In a folding perambulator the combination of a horizontal running gear frame, a folding seat supporting structure embodying pivoted side members arranged over the sides of the running gear frame respectively and adapted to move downwardly into folded relation therewith, a lock- 160

ing bar extending across the running gear frame and having sliding support at its ends thereon and being connected at its ends respectively with the said side members of the seat supporting structure, a handle hinged to the running gear frame and comprising connected side bars, said handle side bars being pivotally connected respectively with the said side members of the seat supporting structure, catches connected together and pivotally fixed to the running gear frame for engaging said locking bar near its ends respectively and holding the handle and seat supporting structure against folding movement when the handle is raised, and means whereby both the said catches may be held out of engagement at the same time.

25. In a folding perambulator the combination of a running gear frame having horizontal side bars, a folding seat supporting structure embodying pivoted side members adapted to fold into a position lengthwise of said side bars respectively, a locking bar movable back and forth with relation to the running gear frame and having sliding sup-

port at its ends upon said side bars and being pivotally connected at its ends respectively with said side members of the folding seat supporting structure, a handle comprising connected side bars hinged to said horizontal bars of the running gear frame respectively and being respectively connected pivotally with the said side members of the seat supporting structure, catches pivotally fixed with relation to the running gear frame, for engaging said locking bar near its ends when the handle is raised and holding the handle and seat supporting structure against folding movement, and guards fixed to the running gear frame for holding said locking bar against upward movement.

In testimony whereof I have signed my name to this specification, in the presence of two subscribing witnesses, on this 7th day of May A. D. 1906.

ALBERT E. MCGILL.
